DESIGN FOR A COMBINED BRUSH FOR
CAMERA LENS AND CONTAINER FOR
CLEANING FLUID

Richard F. Matthews, Huntington Park, Calif.

Application May 4, 1946, Serial No. 129,338

Term of patent 14 years

(Cl. D61—1)

To all whom it may concern:

Be it known that I, Richard F. Matthews, a citizen of the United States, residing in Huntington Park, in the county of Los Angeles and State of California, have invented a new, original, and ornamental Design for a Combined Brush for Camera Lens and Container for Cleaning Fluid, of which the following is a specification, reference being had to the accompanying drawing, forming part thereof:

Fig. 1 is a side elevational view of a combined brush for camera lens and container for cleaning fluid, showing my new design in open position.

Fig. 2 is an end elevational view, looking in the direction of the arrows 2—2 of Fig. 1.

Fig. 3 is an end elevational view, looking from the lower lefthand end of Fig. 1.

Fig. 4 is an end elevational view, looking from the upper righthand end of Fig. 1.

I claim:

The ornamental design for a combined brush for camera lens and container for cleaning fluid, substantially as shown.

RICHARD F. MATTHEWS.
